(57) **CLAIM**

The ornamental design for a light reflector, as shown and described.

DESCRIPTION

FIG. 1 is an isometric view of a light reflector constructed in accordance with the present invention, a lighting fixture being shown in dashed lines as environment;

FIG. 2 is a plan view of the light reflector depicted in FIG. 1;

FIG. 3 is sectional view of the invented light reflector, the section being taken along lines 3—3 of FIG. 2;

FIG. 4 is a sectional view of the invented light reflector, the section being taken along lines 4—4 of FIG. 2;

FIG. 5 is a sectional view of the invented light reflector, the section being taken along lines 5—5 of FIG. 2;

FIG. 6 is a plan view similar to FIG. 2, but showing holes in the light reflector in dashed lines to indicate that such openings are environment; and,

FIG. 7 is a plan view similar to FIG. 2, but showing holes and hole covers in dashed lines to indicate that such features are environment.
